WELDING SHIELD

Filed Feb. 9, 1929

FIG. 1.

FIG. 2.

FIG. 3.

Inventor.

Thomas E. Catherwood

By *Thomas E. Catherwood* A.P.

UNITED STATES PATENT OFFICE

THOMAS EDWARD CATHERWOOD, OF HAGERSVILLE, ONTARIO, CANADA

WELDING SHIELD

Application filed February 9, 1929. Serial No. 338,776.

My invention relates to improvements in welding shields and the object of my invention is to devise a shield which will effectively and completely protect the eyes of the operator from the light rays of the welding flame.

It has been found that the standard shields do not afford absolute protection from the light rays of the welding flame, and in consequence of this many welding operators are habitual sufferers from eye and head aches which are brought on not so much from direct light rays from the flame to the eyes, which of course are very injurious and from which operators are protected by the standard shields, but from reflected light which is quite intense and passes around the back of the shield especially if welding is being done in a normally dark place.

20 My shield is particularly designed to overcome the foregoing difficulties and consists of a device constructed and arranged all as hereinafter more particularly described and illustrated by the accompanying drawings, in which:—

Fig. 1 is a rear perspective view of my device.

Fig. 2 is a vertical cross sectional view through the window and face fitting portion 30 of my shield, and

Fig. 3 is a plan view of my device, the outer portion of the shield being broken away.

Like characters of reference indicate corresponding parts in the different views.

35 My device consists of a substantially curved rectangular shield portion 1 which is of a size sufficient to keep the direct rays of the welding flame away from the face of the operator.

40 Centrally of the shield I position a light filtering glass window 2 and a face fitting guard member 3 which extends rearwardly of the shield from the window 2.

45 Upon reference to Fig. 2 the exact construction and relation of my window and face fitting guard will be clearly seen. Centrally of the shield 1, is formed a rectangular orifice 4 and upon the outer face of the shield around such orifice is attached a rectangular frame 50 5 by a plurality of rivets 6. The outer face

of the frame 5 is of open form and constitutes a bezel in which the coloured glass 2 is contained.

55 My face fitting guard 3 is constructed of soft material such as rubber or pliable leather and is of tubular form. The outer end of such guard is formed to fit the portion of the face surrounding the eyes as will be clearly seen upon reference to Figs. 1 and 3, the upper edge 8 of the member being curved to fit the curvature of the forehead, and the lower edge 9 being curved to follow the curvature of the cheeks underneath the eyes and the bridge of the nose; so that when the face of the operator is pressed comparatively tightly 60 against the resilient outer edge of the guard any outside source of light other than that received through the window 2 will be excluded from the eyes. The inner end 10 of the guard is of the same outer dimensions as 65 the inner dimensions of the frame 5 and such end is inserted thereto. Interiorly of the inner end of the guard I position a metal sleeve 11 which keeps such inner end rigid and retains it in relation to the frame 5, the 70 sleeve being connected to the guard by means of a plurality of rivets 12. In order that the guard may be conveniently held to the operator's face I furnish a handle 13 which extends downwardly from the lower face of 75 the frame 5.

When my shield is being used the operator holds the shield with one hand and presses the outer end of the guard 3 tightly against his face so that the edge of such outer end 80 remains in close all around contact with his face, thus excluding any direct or reflected rays from his eyes other than the filtered rays passing through the window 2.

85 It has been found in practice that my shield as described in the foregoing specification is of great value to the welding operator and that when consistently and correctly used eliminates all eye trouble due to exposure to the direct or reflected rays.

90 What I claim as my invention is:

95 In a device of the character described, a face guard having an orifice therein, a window-containing rectangular frame member surrounding the orifice and extending for-

wardly from the face guard, a single pliable tubular guard for both eyes extending the length of the frame member and protruding rearwardly therefrom, the rear edge of the 5 guard being formed to make close contact with the operator's face at all points of its edge, and a rigid sleeve contained within the tubular guard and the frame and extending rearwardly intermediately of the length of 10 the rearwardly extending protruding portion of the pliable tubular guard to form a support therefor whereby the outer end of the guard remains pliable for light excluding contact with the operator's face.

15 THOMAS EDWARD CATHERWOOD.
